F. R. LINDSTROM.

HARPOON FORK,

APPLICATION FILED JAN. 22, 1917.

1,272,686.

Patented July 16, 1918.

THE NORRIS PETERS CO., PHOTO-LITHO., WASHINGTON, D. C.

UNITED STATES PATENT OFFICE.

FRANK R. LINDSTROM, OF MILACA, MINNESOTA.

HARPOON-FORK.

1,272,686.

Specification of Letters Patent. Patented July 16, 1918.

Application filed January 22, 1917. Serial No. 143,747.

To all whom it may concern:

Be it known that I, FRANK R. LINDSTROM, a citizen of the United States, residing at Milaca, in the county of Millelacs, State of Minnesota, have invented certain new and useful Improvements in Harpoon-Forks; and I do hereby declare the following to be a full, clear, and exact description of the invention, such as will enable others skilled 10 in the art to which it appertains to make and use the same.

This invention relates to hay forks of the harpoon type, and relates more particularly to an improvement on my Patent No. 15 1,205,761 issued November 21, 1916.

An object of the present invention is to provide a novel and improved tripping mechanism for employment in connection with the structure disclosed in my prior 20 patent.

The invention further proposes a single line tripping mechanism for the barb points of the fork whereby their simultaneous actuation to release the load will be assured.

25 With the above and other objects of similar nature in view, the invention consists in the construction, combination and arrangement of parts, set forth in and falling within the scope of the appended claim.

30 In the drawing:

Figure 1 is a front elevation of a hay fork embodying the improved tripping mechanism, the same being shown in inactive position,

35 Fig 2 is a rear view thereof with the tripping mechanism in releasing position parts being broken away,

Fig. 3 is a section taken on the line 3—3 of Fig. 1, and

40 Fig. 4 is a detail section taken on the line 4—4 of Fig. 1.

Referring now more particularly to the drawing, the fork comprises the usual frame 10 including a cross head 11 and spaced 45 parallel leg portions 12, resulting in a longitudinal slot 13 and terminating at their free ends in sharpened points 14. Bridging the legs 12 adjacent their point of connection with the cross head 11 are spaced transverse 50 bracing members 15. Pivoted at one end between said members are a pair of operating handles 16, the upper ends of which project above and are slidably engaged as at 17 with the cross head and adapted for 55 swing movement relatively thereto.

Within the slot 13 adjacent the extremi-

ties of the legs 12 barb points 18 are pivoted, which points in one position extend longitudinally of the legs to permit the latter being readily inserted into a body of hay, and 60 in their other position extend at right angles to the legs and thus grasp the load firmly so that it may be elevated to the desired height. Pivots engaged at their lower ends with the barbs 18 and at their upper 65 ends with rocker links 19 disposed above the brace bars 15, are connecting arms 20, which arms serve to transmit motion to the barbs when it is desired to adjust same to grasp the load.

70 Additional links 21 are employed between the rocker links 19 and handles 16 so that by operating the latter the barbs 18 may be conveniently adjusted. To lock the handles 16 to the cross head 11 so that the barbs 18 will be in alignment with the legs 12, there is 75 mounted on the cross head, a spring plate 22, said plate being secured in position by means of bolts 23 and having its ends bent to provide resilient clips 24 adapted to readily engage the related handle. It is thus evident that the fork may be readily plunged into a body of hay without danger of displacing the barbs 18 and that, when it is desired to operate the latter to grasp the 80 load, the handles are merely disengaged from the clips and swung outwardly on their pivots and the barbs thus operated through the medium of the link and arm connection above described. It will be noted that in 85 this position the upper ends of the arms 20 will be disposed inwardly of the pivot points of the rocker links 19 and any tendency for downward movement of the barbs under the influence of the load will thus be prevented.

90 In order to simultaneously release the barb points 18, there is pivoted at 26 between the bracing members 15 an L-shaped lever 27 provided in one end with an eye 28 100 in which is engaged one end of a trip line 29. Pivots connected with the lever 27 at opposite sides of its pivot are the inner ends of a pair of oppositely extending operating bars 30, said bars being disposed between 105 the bracing members 15 and being slotted longitudinally at 31 intermediate their ends to receive the pivot bolts 32 in which the handles 16 are mounted. The outer or free ends of the bars 30 are adapted for engagement with the connecting arms 20 so that by 110 pulling upon the trip line 29 the lever 27

and bars 30 will be moved to the position shown in Fig. 2 thereby forcing the arms 20 outwardly beyond the center lines between the pivots of the barb points 18 and links 19, whereupon the barb will move under the influence of the load in the fork, into alignment with the legs 12, the load being then released and the handles 16 swing inwardly and locked beneath the slips 24.

- 10 What I claim is:—
A harpoon fork comprising an inverted substantially U-shaped frame, barbs fitted to the frame, a cross bar secured in the frame spaced from its closed end, handles 15 pivoted to the cross bar and operatively connected with the barbs to move and retain

the latter in carrying position, an L-shaped lever pivoted to the cross bar, and operating bars pivoted to the lever on opposite sides of its axis of movement and having slotted 20 portions receiving the pivots for said handles to guide the outer ends of said operating bars into abutting engagement with the connections between the barbs and handles, substantially as described. 25

In testimony whereof, I affix my signature, in the presence of two witnesses.

FRANK R. LINDSTROM.

Witnesses:

C. E. ERICKSON,
JOHN A. PETERSON.
